(57) CLAIM

The ornamental design for pet bath massage brush, as shown and described.

DESCRIPTION

FIG. 1 is a perspective view of a pet bath massage brush showing my new design;

FIG. 2 is a front elevational view thereof;

FIG. 3 is a rear elevational view thereof;

FIG. 4 is an enlarged right side elevation view thereof;

FIG. 5 is an enlarged left side elevation view thereof;

FIG. 6 is a bottom plan view thereof; and,

FIG. 7 is a top plan view thereof.

The features shown in broken lines illustrate environmental structure and form no part of the claimed design.

1 Claim, 7 Drawing Sheets
